INVENTOR.
HENRI A. SEVIGNE
BY *A. W. Harrison*
ATTORNEY

UNITED STATES PATENT OFFICE.

HENRI A. SÉVIGNE, OF WINTHROP, MASSACHUSETTS, ASSIGNOR TO NATIONAL BREAD WRAPPING MACHINE COMPANY, OF BOSTON, MASSACHUSETTS, A CORPORATION OF MASSACHUSETTS.

WRAPPING MACHINE.

Application filed June 10, 1926. Serial No. 114,879.

This invention relates to wrapping machines and has particular reference to means for facilitating the operation of attending to the supply of un-wrapped articles, such as 5 loaves of bread, to the machine, and the removal of the wrapped articles therefrom.

One of the objects of the invention is to enable a single attendant to transfer the un-wrapped articles from a source of supply such as a movable rack of shelving such as commonly employed in bakeries, to feeding position where they will begin to pass automatically to and through the wrapping machine, and to also remove the wrapped 10 articles in closely assembled groups delivered from the machine and place them elsewhere such as on another rack without having to gather the wrapped articles together into a group, doing both while remaining 15 in one position adjacent to the machine, thereby saving time in the use of the machine and enabling it to be attended to by one person instead of two.

Another object is to provide for counting 20 the wrapped articles issuing from the machine, this being effected by ensuring the successive deposit of said articles in a receptacle to form groups each of which groups includes a closely assembled predetermined number of said articles.

With the above mentioned objects in view, and others hereinafter referred to, the invention consists in the construction and combination of parts substantially as hereinafter described and claimed.

Of the accompanying drawings:—

Figure 1 is a perspective view of my improvements illustrated as at the delivery end of a bread wrapping machine of the type 40 illustrated in Letters Patent No. 1,412,754, issued April 11, 1922, to Sévigné & Arnold.

Figure 2 is a detail elevation looking in the direction of the arrow 2, Figure 1, and illustrating the tilting shelf as swung down 45 by the weight of a wrapped loaf indicated by dotted lines X.

Similar reference characters designate similar parts or features in both of the views.

As explained in the patent referred to, un-wrapped articles are deposited on a feeder consisting of inclined rods 42 sup-

ported by brackets one of which is shown at 41, and said articles, after being wrapped by the mechanism of the machine, are 55 pushed over an apron 241 by pushers 214 carried by chains 209. The preceding numerals are the same as those used for the same parts illustrated and described in said patent.

Reference letters instead of numerals are employed herein for the features of my present improvements.

The loaves are forwarded by the pushers 214 onto a belt *a* mounted on rolls *a'*, *a''*, and said belt delivers the loaves singly and successively onto an automatically tilting shelf *b* having an upright wall *b'*. Said shelf normally occupies the position indicated in Figure 1, level with or slightly below the plane of the upper stretch of the belt *a*. It is loosely supported by a pivot *c* carried by a bracket *d* secured to a stationary rod *d'* which is suitably supported by the frame of the machine.

To normally hold the pivoted shelf in its loaf-receiving position, which position is determined by a stop presently described, the shelf has a rod *b''* extending from it, on which rod a weight *b''* is adjustably mounted. If desired, a spring *e* may be employed either to aid the weight or as a substitute therefor.

The counterbalance of the shelf is such that the weight of a wrapped loaf arriving thereon from the belt *a* tilts said shelf (see Figure 2) so that the loaf will slide onto an elongated laterally inclined receiving shelf *f* having a stop wall *f'* at its lower edge, said shelf constituting a temporary receptacle for a predetermined number of wrapped loaves. The said shelf *f* is carried by a bracket *f''* projecting from an upright or leg of the machine, said bracket also supporting a slideway *f'''* for a rod *k* hereinafter described. To guide the sliding loaf onto the shelf *f* and to determine the lower or tilted position of the shelf *b*, the shelf *f* has an extension or plate *f''''* the upper edge of which is just overlapped by the end of the shelf *b* when the latter is tilted. The plate *f''''* has a side wall *f'''''* to which is adjustably secured an upright strip *g* having a lateral tip *g'* provided with a cushion *g''* of rubber.

or other suitable material in position to act as a stop for the upper edge of the wall b' of the tilting shelf, thereby determining the normal upper position of said shelf under the influence of the weight b^3 or spring e .

Movable along the receiving shelf f is a pusher h having a side wall h' and carried by a rod h^2 which, in turn, is carried by a stud i secured to a rod k mounted to slide 10 in the portion f^3 of the fixed bracket f^2 hereinbefore described. Connected to an intermediate portion of the slide rod k by a link l is a lever m pivoted at n to a bracket o mounted on an upright or leg of the machine frame, the other end of the lever being pivoted at p to a link or rod r which is reciprocated by suitable means such as a crank of one of the shafts of the wrapping machine, not necessary to illustrate. Preferably the lever m is actuated as many times per minute as loaves are wrapped, to effect the results of the operation now to be described.

Each wrapped loaf delivered by a pusher 25 214 onto the belt a is delivered by the latter onto the shelf b which then immediately tilts so that the loaf slides down over the plate f^2 onto the shelf f , and said shelf b then returns to its normal upper position to be 30 ready to receive another loaf from the belt a . The timing is such that usually the pusher h is in the position illustrated by Figure 1 so that the loaf arrives against the shelf wall f' in front of the pusher h , and the latter 35 then moves in the direction of the arrow and slides the loaf toward the other end of the shelf f . If it should happen that another loaf starts over the plate f^4 before the pusher has retreated, it will be temporarily arrested 40 by the rearwardly extending stop wall h' of the pusher until the pusher has fully retreated, after which said loaf will then slide down in front of the pusher.

The distance of reciprocation of the 45 pusher h is such that it will advance each loaf an amount of travel slightly exceeding the width of the loaf so that, when the pusher retreats, a space will be formed for the admission of the next loaf delivered by 50 the tilting shelf b . The next advance of the pusher h will then slide two loaves along the receiving shelf f , and so on, resulting in effecting a close assemblage of the wrapped loaves in side-by-side contact so that a group 55 of them can be picked up together for transfer to a rack or box without loosening any of the sealed portions of the wrappers.

A single attendant in a position near the 60 far end of the shelf f is also near the end of the gravity slide rods or feeder 42, and therefore, with a rack of un-wrapped loaves and an empty rack within reach, said attendant can, without moving from that position, alternately attend to supplying the machine feeder with un-wrapped loaves and to

removing the wrapped loaves, placing the latter on the shelves of the empty rack either in uncertain numbers or in counted groups as presently explained. The single attendant can do this with ease because the loaves, 70 as they accumulate on the shelf f , are always moving in the same direction as that in which he moves to place fresh loaves on the gravity feeder 42.

The present invention possesses a number 75 of advantages in addition to what has been specifically mentioned. It enables the machine as a whole to occupy less floor space than when a long belt or run-way is employed to hold a quantity of loaves until an 80 attendant can pick them up. It avoids the necessity of using any turn-table such as has been proposed for starting the wrapped loaves in a new direction for removal or packing. And the cooperating shelves b and f constitute an effective counting mechanism. 85 For instance, assuming that the shelf f and its wall f' are of a length to receive and which necessarily are grouped in contact 90 with each other on the said shelf, the attendant knows that when the foremost loaf is at the end of the wall f' he is to pick up four loaves. He need not count them himself. Then when three such groups of four each 95 have been removed, he has taken just a dozen wrapped loaves from the machine. This is of particular utility when the removed loaves are packed in cartons located at hand instead of being placed on the usual movable racks of shelving. 100

The reason for terminating the wall f' short of the end of the shelf f is that if some temporary duty prevents the attendant from 105 picking the loaves up and wrapped loaves continue to arrive on and be pushed along the shelf, the extra loaves pushed beyond the end of the wall f' can be received in a suitable basket or other receptacle placed for that purpose. Another reason for so terminating the wall f' is that it leaves an open 110 space through which an attendant can, if he wishes, swing the row or group of loaves which he has grasped, instead of lifting them up over the top of the wall f' . 115

A wrapping machine equipped with my present improvements delivers the wrapped articles properly and conveniently grouped, without requiring any timing mechanism. Whether or not the wrapping machine is 120 operating with regularity, each article issuing from the machine automatically effects the delivering action of the tilting shelf. And the latter is also true if the delivery belt of the wrapping machine slips or if 125 the articles slip on such belt.

While the mechanism illustrated and designated by reference letters is especially adapted for use with machines for wrapping loaves of bread, it is to be understood that 130

I do not limit myself thereto as said mechanism is also useful for delivering and counting other wrapped articles.

I desire it to be also understood that I do not limit myself to machines having a gravity slideway for the feeder which starts the articles in to the wrapping mechanism, as any other suitable type of feeder may be employed such as the horizontal belt feeder illustrated in Letters Patent No. 1,253,636 issued January 15, 1918, to Sévigné & Arnold.

Having now described my invention, I claim:

15 1. A wrapping machine having means for automatically starting articles on their way to be wrapped, a horizontally movable carrier for transporting the wrapped articles, a receptacle in position of adjacency to both

20 the first-mentioned means and said carrier, and means for automatically directing the wrapped articles laterally from said carrier and delivering them to said receptacle.

25 2. A wrapping machine having a feeder for articles to be wrapped and a receptacle for the wrapped articles, both the feeder and the said receptacle being at one side of the machine and within manual reach of an attendant remaining in one position, said receptacle having means for effecting the gathering of the articles thereon in close relationship.

30 3. A wrapping machine having a substantially horizontal delivering belt, a tilting shelf having a side edge in proximity to the delivering end of said belt, the free end of said shelf extending to one side of the machine, and a receptacle in position to receive the wrapped articles from said tilting shelf.

35 4. A wrapping machine having a delivery carrier at its end, a laterally inclined receiv-

ing shelf at one side thereof, means for automatically moving the articles along said shelf, and a tilting member for receiving articles from said carrier and discharging them onto said shelf.

45

5. A wrapping machine having a delivery carrier at its end, a receiving shelf at one side thereof, a laterally tilting member for receiving articles from said carrier and discharging them onto said shelf, and a pusher for sliding the articles along said shelf.

6. A wrapping machine having a delivery carrier at its end, a laterally inclined receiving shelf at one side thereof, a laterally tilting member for receiving articles from said carrier and discharging them onto said shelf, and a pusher for sliding the articles along said shelf, said pusher having a rearwardly extending stop wall.

55

7. A wrapping machine having a substantially horizontal delivering belt, a tilting shelf having a side edge in proximity to the delivering end of said belt, the free end of said shelf extending to one side of the machine, and a receptacle in position to receive the wrapped articles from said tilting shelf.

60

8. A wrapping machine having a substantially horizontal delivering belt, a tilting shelf having a side edge in proximity to the delivering end of said belt, the free end of said shelf extending to one side of the machine, a receptacle in position to receive the wrapped articles from said tilting shelf, and means for pushing the articles along said receptacle in a direction substantially parallel with the side of the machine.
